COMBINATION LAMP AND TELEVISION ANTENNA

Theophile A. Stiffel, Chicago, Ill.

Application September 7, 1949, Serial No. 114,387

2 Claims. (Cl. 250—33)

1
This invention relates to a combination lamp and television antenna.

Television antennae of the indoor-type, as presently constructed and in general use, are intended to be positioned on top of the cabinet of a television receiving apparatus. As is well known, the particular forms of television antennae, currently in use, do not blend in with many decorative schemes and consequently they tend to detract from the decorations in the room in which the television receiving apparatus may be located. Such indoor-type television antennae usually include a weighted base member on which are pivotably supported a pair of extensible telescoping rod-like members. The use of such antennae prevent the use of decorative lamps or other objects on the top of the cabinet housing the television apparatus.

Additionally, it is generally recognized that the viewing of a television screen in a completely darkened room is detrimental to the eyes of the viewers and that a subdued light in the room in which the television receiving apparatus is located is materially beneficial. Further, a great number of the television receiving sets currently in use are not equipped with illuminated control panels, therefore rendering it difficult to see the control dials for tuning the apparatus.

Accordingly, it is an object of my invention to incorporate in the structure of a decorative lamp, either of the floor or table type, a television antenna which may be completely disguised from view, or caused to be blended into the general lamp structure so as to not readily be perceptible.

Another object of my invention is the provision of a combined lamp and television antenna which is pleasing in appearance, thereby enhancing the attractiveness of the room decorations when placed on top of a television receiving cabinet.

A further object of my invention is the provision of a combined lamp and television antenna in which the lamp provides beneficial illumination for viewing the television screen and for manipulating the control dials for tuning of the apparatus.

Other and further objects of my invention will be apparent from the following description when considered in connection with the accompanying drawings in which:

Fig. 1 is a side elevational view of a table lamp showing a television antenna applied thereto, the shade being shown in cross section.

Fig. 2 is a cross sectional view taken substantially on line 2—2 of Fig. 1.

Fig. 3 is a fragmentary elevational view looking in the direction of the arrows 3—3 of Fig. 1.

2
Fig. 4 is an elevational view of a modified embodiment of my invention, the lamp shade being shown in cross section.

Fig. 5 is a cross sectional view taken substantially on line 5—5 of Fig. 4.

Fig. 6 is an elevational view of another modified embodiment, the shade being shown in cross section.

Fig. 7 is a cross sectional view taken substantially on line 7—7 of Fig. 6.

Fig. 8 is a fragmentary elevational view looking in the direction of the arrows 8—8 of Fig. 6.

Fig. 9 is an exploded view, in perspective, showing certain details of construction.

Referring particularly to the embodiment illustrated in Figs. 1—3 inclusive, the numeral 15 indicates, generally, a lamp standard and base which may be of any desired configuration. Supported on the standard 15 is a plate member 16

20 of insulating material, preferably transparent or translucent, the said plate member having a central aperture 16a through which the inner tubular member 15a of the lamp standard 15 projects. As illustrated in Fig. 9, the upper end of the said

25 member 15a is threaded to receive a nut 17 which serves to secure the plate member 16 on a shoulder 15b provided on the standard, and also to receive the threaded end of a conventional electric light socket 18 which carries an electric light bulb 19.

30 Suitably supported on the plate member 16 are spaced rod-like elements 21, each having at their ends, a downwardly inclined portion 22 terminating in an upturned portion 23 providing a retaining hook-like end to support a conventional lamp shade 24.

35 Supported on plate member 16 are antenna rods 26 which extend substantially parallel to the shade supporting elements 21. As will be clearly seen in Fig. 2, the antennae rods 26 are 40 substantially coaxially arranged with the inner ends of the rods in spaced relation. Each of the rods 26 has a conducting wire such as 27 connected thereto.

45 As will be apparent by reference to Fig. 1, the lower edge of the lamp shade 24 is disposed in a plane below the plane of the plate member 16. Thus, the plate member 16 and the associated antennae rods 26 are confined within the limits of the shade 24 and are effectively hidden from 50 view, the appearance of the lamp being that of any conventional lamp.

While the conducting wires 27 are shown as connected to the outer ends of the antenna rods 26, it will be apparent that the wires may be 55 connected to the inner ends which are proximate to each other, and that the wires may be suitably

conducted through the hollow standard 15 and emerge through the bottom of the base, so as to be substantially completely hidden from view.

Similarly, as in the conventional practice of tuning a television receiver by rotating the indoor television antennae about a vertical axis, the lamp may be moved about its vertical axis so as to properly position the antenna elements 26 in order to obtain the most effective reception.

In the embodiment illustrated in Figs. 4 and 5, a plate member 27 is suitably mounted on a lamp standard and base, indicated generally, by the numeral 28. The plate member 27 which is of insulating material is secured to the standard 28 by a nut 29 in threaded engagement with the upper end of the inner tubular member of the lamp standard 28. The means of attachment of the plate member 27 to the standard 28 may be identical with that hereinabove described and illustrated in Fig. 9. A harp 30 is mounted on the end of the inner tubular member 31 and is secured thereto as by nut 32. A socket 33 and light bulb 34 are supported on the inner tubular member 31 in the conventional manner. The harp 30 is provided at the top thereof with a shouldered stud 36 adapted to support a conventional lamp shade 37, the said shade being secured on the harp 30 by a threaded ornamental cap 38.

Suitably secured to the plate member 37 is a pair of antenna elements 39. The said elements are preferably formed of telescoping sections so as to render the elements extensible and retractable and may be spaced on the plate member 27, preferably near the ends of the said plate member. The antenna elements 39 are intended to be extended, if necessary, when the television receiving apparatus is in use, the said elements in such a case projecting above the upper level of the shade 37.

As will be clearly apparent by reference to Fig. 4, the plate member 27 is disposed in a plane above the lower edge of lamp shade 37, while the upper ends of the antenna elements 39, when in fully retracted position, are disposed below the top edge of the lamp shade. Thus, when the apparatus is not in use, the antenna elements 39 are hidden from view and the appearance of the lamp is as any conventional table lamp. Conducting wires 40 are connected to the antenna elements 39.

In the embodiment shown in Figs. 6 through 8, a transparent or translucent insulating plate member 41 is suitably mounted on a standard and base 42 in a manner similar to that illustrated in Fig. 9. The said plate member 41 carries a pair of spaced rod elements 43 constructed and formed similarly to the rods 21, illustrated in Figs. 1 and 2, the rod elements 43 being adapted to support a lamp shade 44, in the manner hereinabove described. A conventional socket 45 and light bulb 46 are mounted on standard and base 42.

Suitably secured to the plate member 41, proximate to the center portion thereof, are two pairs of lugs 47, each pair of said lugs being adapted to pivotally support therebetween a television antenna element 48. The said antenna elements 48 may be of the telescoping type so as

to be extensible and retractable axially. Conducting wires 49 are connected to the antenna elements 48. As will be apparent, the antenna elements 48, for purposes of tuning, may be adjusted axially and may be moved about their pivotal axes. Additionally, the lamp may be turned about its vertical axis to any desired position in order to obtain the most effective reception.

The plate member 41 is disposed above the lower edge of the lamp shade 44, while the upper ends of the antenna elements 48, when in fully retracted position are disposed below the top edge of the lamp shade. Thus, when the television receiving apparatus is out of use, the antenna elements 48 may be retracted, as shown in Fig. 6, so as to be completely hidden from view within the shade 44.

While my invention has been described as applied to a table lamp, it is to be understood that the invention may be applied to a floor lamp and that various changes in the shape, size, and arrangement of parts may be resorted to, without departing from the spirit of my invention or the scope of the appended claims.

I claim:

1. A device for positioning on the cabinet of a television receiver comprising a movable lamp having a standard and a lamp shade, a plate member carried on said standard, a plurality of lamp shade supporting elements carried on said plate member, said elements having end lamp shade engaging portions disposed below the plane of said plate member, and television antennae elements supported on said plate member and lying substantially in the plane thereof within the confines of said shade so as to be substantially hidden from view, said lamp providing beneficial illumination for viewing the television screen and being movable about a vertical axis for tuning of said antennae elements.

2. A device for positioning on the cabinet of a television receiver comprising a movable lamp having a standard and a lamp shade, a plate member carried on said standard, a plurality of lamp shade supporting elements carried on said plate member, said elements having end lamp shade engaging portions disposed below the plane of said plate member, a pair of television antennae elements supported on said plate member in substantially upright position within the confines of said shade, said lamp providing beneficial illumination for viewing the television screen and being movable about a vertical axis for tuning of said antennae elements.

THEOPHILE A. STIFFEL.
